FIG. 1.

FIG. 2.

INVENTOR.

Lewis W. Helmuth

UNITED STATES PATENT OFFICE

111,967

DESIGN FOR A NIGHTSHIRT

Louis W. Helmuth, Lakewood, Ohio

Application September 28, 1937, Serial No. 71,840

Term of patent 14 years

To all whom it may concern:

Be it known that I, Louis W. Helmuth, a citizen of the United States, residing in Lakewood, Ohio, in the county of Cuyahoga and State of Ohio, have invented a new, original, and ornamental Design for a Nightshirt, of which the following is a specification, reference being had to the accompanying drawing, forming a part thereof.

Fig. 1 is a front view of a nightshirt showing my design; and

Fig. 2 is a rear view of the nightshirt shown in Fig. 1.

I claim:

The ornamental design for a nightshirt, substantially as shown.

LOUIS W. HELMUTH.
